UNITED STATES PATENT OFFICE

2,195,283

STAPLING MACHINE

George C. Passek, Philadelphia, Pa., assignor to
Alfred J. Paynter, Philadelphia, Pa.

Application February 9, 1939, Serial No. 255,421

3 Claims. (Cl. 1—49)

This invention relates to improvements in stapling machines having the general characteristics of the machine illustrated and described in my Letters Patent No. 2,150,127, dated March 7, 1939, and including a guide for a row of staples, a staple passage for receiving staples successively from the guide, a driver for driving the staples through and from the passage and into the work to be stapled, and a member movable from a normal position by the engagement therewith of a staple driven through the passage by the driver and being automatically returnable to its normal position when released.

The object of the invention is to provide a novel and advantageous means or mechanism operated by the said member for preventing a staple from leaving said guide and entering the passage after the starting of a staple driving operation and before the completion of the driving operation, for preventing staples from clogging or choking the staple passage and for ensuring the proper operation of the machine.

The invention resides in the elements and the combinations of them, as will be hereinafter described and claimed.

In the accompanying drawing, illustrating the invention:

Figure 1 is a longitudinal section of my improved machine, on line 1—1 of Fig. 2.

Figure 2 is a vertical section through the forward part of the machine, on line 2—2 of Fig. 1.

Figure 3 is a view of a portion of Fig. 1, showing the positions of the parts at the completion of a staple driving operation.

Figure 4 is a transverse section of the machine, on line 4—4 of Fig. 1, enlarged.

Referring to the drawing, 3 designates the machine frame having a horizontally-extending lower portion 5 and a vertically-extending forward portion 6 rising from the forward end of the lower portion.

The lower portion 5 of the frame is hollow and has a floor plate 7 secured thereto and provided with a hollow, longitudinally extending staple guide 8 for receiving and guiding a row of staples 9.

Slidably mounted in the forward end portion of the staple guide 8 is a staple supporting and forming member 10 having an inclined forward end surface 11. The member 10 has a rod 12 secured thereto and extending rearwardly therefrom through and beyond a bracket 13 which is fixed within the stationary staple guide 8, and the member 10 is urged forwardly by a spring 14

which encircles the rod 12 between the member 10 and a loose collar 15 on the rod 12, the collar 15 engaging the bracket 13.

The member 10 is movable rearwardly from its normal position, shown in Fig. 1, to the position shown in Fig. 3, against the action of the spring 14, and, after the member has been moved to the position shown in Fig. 3, and released, the spring 14 acts to automatically move the member forwardly and to return it to its normal position. After the spring 14 has moved the member 10 forwardly to its normal position, the further forward movement of the member is prevented by a gear rack 16 which is secured to the rearward end portion of the rod 12, and which is stopped by the bracket 13, as illustrated.

The row of staples 9 is fed forwardly by a suitable follower 17 which embraces the staple guide 8 and is slidably thereon. The follower has a part 18 which extends upwardly through a longitudinal slot in the top wall of the lower portion 5 of the frame 3. The part 18 is connected to the outer end portion of a spiral spring 19 which surrounds a shaft 20 fixed in the frame 3, and has its inner end secured to the shaft. The spring 19 tends to wind itself around the shaft 20 and thereby urges the follower 17 and the row of staples 9 engaged thereby forwardly and presses the foremost staple 21 of the row of staples against the forward frame plate 22.

The foremost staple 21 embraces the forward end portion of the forming member 10 and the staple occupies a position within a staple passage 23 having an open bottom and being formed between the forward end of the staple guide 8 and the frame plate 22, and between side plates 24, 24 secured within the machine frame and constituting, in effect, a part thereof.

Slidably mounted in the forward portion 6 of the frame 3 between the side plates 24, 24 thereof and above and in the alignment with the foremost staple 21 is a staple driving plate 25 constructed and arranged to be moved downwardly from its normal position shown in Fig. 1 and through the staple passage 23 to the position shown in Fig. 3 to drive the said foremost staple downwardly through and discharge it from the open lower end of the passage.

The staple driver 25 has a bracket 26 secured thereto and pivotally connected to the lower end of a link 27 whose upper end is pivoted on a pin 28 carried by a lever arm 29 which is fulcrumed on a pin 30 in the forward portion 6 of the machine frame. The link 27 and the fulcrumed end portion of the lever arm 29 are housed within

the machine frame, and the free end portion of the lever arm extends out through a slot 31 in the frame and forms a handle 32 which may be lowered and raised to effect staple driving operations.

5 The staple driver 25 and its operating lever arm 29 are maintained normally elevated by springs 33, 33 on the respective sides of the lever arm 29. Each of these springs is coiled around 10 the fulcrum pin 30 and has one end thereof engaged with the pivot pin 28 and the other end thereof engaged with a transverse pin 34 fixed in the machine frame. The lever arm 29 is moved against the action of the springs 33, 33 when the 15 arm is lowered to effect a staple driving operation, and, thereafter, the springs act to elevate the arm to its normal position.

10 The opposing side walls of the staple passage 23 formed by the inner surfaces of the side plates 24, 24 are curved and directed inwardly and provide staple leg deflecting parts 35, 35 at the 20 sides of the delivery end of the staple passage 23. The curved surfaces of these deflecting parts 35, 35 extend below the plane of the bottom of the forming member 10 and they are spaced from 25 corners or obstructions 36, 36 formed by the member 10 at the junctions of the bottom surface and side surfaces thereof.

20 The gear rack 16 which is moved rearwardly and forwardly by the forming member 10 is in mesh with the lower portion of a pinion 37 which rotates freely on a shaft 38 carried by and extending between the side walls of the stationary 25 staple guide 8. The upper portion of the pinion 37 is in mesh with a gear rack 39 secured to the rearward end portions of two parallel rods or pins 40, 40 which are slidably fitted within 30 holes or openings formed by and between the top wall of the staple guide 8 and the forming member 10. The gear racks 16 and 39 and the interposed pinion 37 are constructed and arranged to cause the rods or pins 40, 40 to be projected forwardly from the normal position thereof, shown in Fig. 1, to the position shown in Fig. 3, 35 when the forming member 10 is moved rearwardly from its normal position, shown in Fig. 1, to the position shown in Fig. 3, and to cause the rods or pins 40, 40 to be withdrawn rearwardly from the position shown in Fig. 3 to the normal 40 position shown in Fig. 1, when the forming member 10 is returned by the spring 14 to its normal position shown in Fig. 1, after being moved to the position shown in Fig. 3 and released.

45 The staple driver 25 has parallel, vertically extending slots 41, 41 therein through which the rods or pins 40, 40 move when they are moved forwardly from the normal position shown in Fig. 1, as and for a purpose hereinafter described.

50 The operation of the machine is as follows: 55 The machine is placed over the work to be stapled with the bottom surface of the machine in contact with the work and with the staple passage 21 over the part of the work which is to receive the staple.

60 The operating arm 29 is then depressed or forced downwardly against the action of the springs 33, 33, thereby forcing the staple driver 25 downwardly and causing it to engage the top of the crown of the foremost staple 21 of the 65 row 9 and drive the staple 21 downwardly through the passage 23 and discharge the staple through the open lower end of the passage.

70 During the downward movement of the staple 21, the staple is guided by the walls of the passage 23. While the staple 21 is being driven

75 downwardly, the bottom of the crown thereof engages the inclined forward end surface 11 of the forming member 10 and thereby moves the member 10 rearwardly between the legs of the staple 21 and against the action of the spring 14 until the member 10 has been moved completely out of the path of the staple crown, as the crown passes the lower end of the inclined surface 11; and, while the staple 21 is thus being driven downwardly, the lower ends of the legs of the 10 staple encounter the curved surfaces of the deflecting parts 35, 35 of the plates 24, 24 and are forced between such surfaces and the opposing corners 36, 36 of the forming member 10. As the legs of the staple 21 are thus forced between 15 the curved surfaces of the deflecting parts 35, 35 and the opposing corners 36, 36, the pressure of the staple legs against the corners 36, 36 and against the plates 24, 24 at and above the curved 20 surfaces of the deflecting parts 35, 35 thereof, the staple legs are curved and directed inwardly, as shown in Fig. 2 by dot-and-dash lines, illustrating a staple driven part way through the passage 23, and such curving of the staple legs continues until the staple has been forced completely through the passage 23 and discharged from the open lower end thereof.

25 As the staple is thus driven through and discharged from the passage 23 the staple legs are curved and forced into the work or article being 30 stapled the same as in the machine shown and described in my Letters Patent No. 2,150,127, previously referred to.

35 After a staple has been driven, as just described, the downward pressure on the lever arm 29 is removed and the springs 33, 33 raise the lever arm and the staple driver 25 to the normal position; and, as the staple driver clears the forming member 10 and the row of staples 9, the spring 14 moves the forming member forwardly 40 to its normal position, and the spring 19 advances the follower 17 and row of staples 9, and moves the foremost staple of the row into the staple passage 23 beneath the driver 25 for a 45 succeeding staple driving operation.

50 As the forming member 10 is moved rearwardly during each staple driving operation, the rods or pins 40, 40 are projected forwardly through the slots 41, 41 in the driver 25; and, while the pins are within the slots, the pins constitute obstructing elements which are adapted to be engaged by the bottom walls of the slots 41, 41 to thereby prevent the raising of the driver 25 sufficiently to permit another staple to enter the staple passage 23. The staple driver 25 is prevented from being thus raised until after the staple being driven has been discharged from the staple passage 23, because the binding action of staple legs against the deflecting parts 35, 35 and corners 36, 36 of the forming member 10 prevents the forward movement of the member 10 and consequently prevents the rearward movement of the pins 40, 40 until the staple being driven has been driven far enough to clear the forming member 10 and to be discharged from the staple passage 23, even though the driver 25 should be accidentally raised within the limits allowed by the slots 41, 41 prior to the completion of a staple driving operation. Thus it will be seen that after each staple has been moved from the 55 staple guide 8 into the passage 23 it will be impossible for the next succeeding staple to enter the passage 23 until the staple within the passage has been discharged therefrom by the staple driver 25, thereby effectively preventing the staples 60

from clogging or choking the staple passage 23 and ensuring the proper operation of the machine.

I claim:

- 5 1. In a stapling machine, the combination of a frame having staple feeding and guiding means; a staple driver operable to drive a staple through and discharge it from said guiding means; and obstructing means to limit reverse movement of 10 the driver until the completion of a staple driving operation; said obstructing means comprising an obstructing element movable into an obstructing position in the path of a part of the driver, a block slidably mounted in the frame and urged to a position to be engaged and moved by 15 a staple driven by the driver, and means operated by said block to move said element to its obstructing position.
2. In a stapling machine, the combination of a 20 frame having staple feeding and guiding means; a staple driver operable to drive a staple through and discharge it from said guiding means; and obstructing means to limit reverse movement of the driver until the completion of a staple driving 25 operation; said obstructing means comprising an obstructing element movable into an obstructing position in the path of a part of the driver, a block slidably mounted in the frame

and urged to a position to be engaged and moved by a staple driven by the driver, a gear rack movable by and with said element, a gear rack movable by and with said block, and a pinion interposed between and in mesh with said racks, 5 whereby the movement of said block by a staple will cause the movement of said element to its obstructing position.

3. In a stapling machine, the combination of a 10 frame having staple feeding and guiding means; a staple driver operable to drive a staple through and discharge it from said guiding means; and obstructing means to limit reverse movement of the driver until the completion of a staple driving 15 operation; said obstructing means comprising an obstructing element movable into an obstructing position in the path of the driver, a block movably mounted in the frame and urged to a position to be engaged and moved by a staple 20 driven by the driver, and means operated by said block to move said element to its obstructing position, said guiding means and said block having cooperating staple bending parts causing said block to be frictionally held against reverse movement until the completion of the staple driving 25 operation.

GEORGE C. PASSEK.
